J. W. WEISMANTEL.
COMBINATION BED ATTACHMENT.
APPLICATION FILED JULY 10, 1919.

1,358,502.

Patented Sept. 21, 1920.

Inventor:
Joseph W. Weismantel,
By the Attorneys

Braantzel and Richards.

UNITED STATES PATENT OFFICE.

JOSEPH W. WEISMANTEL, OF NEWARK, NEW JERSEY.

COMBINATION BED ATTACHMENT.

1,353,502.

Specification of Letters Patent. Patented Sept. 21, 1920.

Application filed July 10, 1919. Serial No. 309,908.

To all whom it may concern:

Be it known that I, JOSEPH W. WEISMANTEL, a citizen of the United States, residing at Newark, in the county of Essex and State of New Jersey, have invented certain new and useful Improvements in Combination Bed Attachments; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in that class of devices known in the art as combination bed-attachments; and, the present invention has reference, more particularly, to a novel and useful attachment for beds which is adapted for use as a head or back-rest, a pillow-sham holder, a table, or a means for preventing drafts of air from blowing upon the person lying in the bed.

The present invention has for its principal object to provide an attachment of the general character hereinafter fully set forth, which is easily applied in various positions upon the frame of the bed, and is adjustable into different positions, so as to be used for the support of the head or shoulders, at any desired angle, but which is also adapted for use as a pillow-sham holder; or, when slid into and fastened in other positions with relation to the bed, may be used as a serving or reading table, or as a work bench.

The invention has for its further object to provide an attachment which may also be fastened at the side of the bed, and in such position protect the person in bed from the cold or strong air-drafts blowing into the bed-room from an opened window or door.

Other objects of the present invention not at this time more particularly enumerated will be clearly understood from the following detailed description of the same.

With the various objects of the invention in view, the invention consists, primarily, in the novel device, attachment or apparatus of the character hereinafter more fully described and for the purposes hereinabove stated; and, the invention consists, furthermore, in the novel arrangements and combinations of the several devices and parts, as well as in the details of the construction

of the said parts, all of which will be more particularly set forth in the following specification, and then finally embodied in the clauses of the claim which are appended to, and which forms an essential part of the said specification.

The invention is clearly illustrated in the accompanying drawings, in which:

Figure 1 is a perspective view of a bed, showing also in perspective the combination bed-attachment made according to and embodying the principles of the present invention, said view illustrating in connection therewith the various uses for which the attachment is adapted; and Fig. 2 is a perspective view, showing in detail a portion of one of the side-rails of the bedstead, a pair of slides movably and detachably connected with said rail, a fragmentary portion of one of the posts forming part of the attachment, and a connecting brace or stay-rod between said post and one of said slides.

Fig. 3 is a perspective view, showing in detail a portion of a foldable head-rest for use with the attachment.

Similar characters of reference are employed in the said above described views, to indicate corresponding parts.

Referring now to Fig. 1 of the drawings, the reference-characters 1 and 2 indicate the respective end-frames of a bedstead, and 3 and 4 the two side-rails of the same which are of any suitable construction, and are suitably connected in any usual manner to the respective corner-posts 5 of the said end-frames. The said side-rails, as will be seen from an inspection of Fig. 2 of the drawings, are preferably, L-shaped in cross-section, and movably mounted upon each side-rail are a pair of slides, as 6 and 7, which are provided with clamping means, usually in the form of clamping screws 8 and 9, for securing said slides in their desired adjusted positions, as will be clearly evident from an inspection of the several figures of the drawings. Extending vertically and suitably connected with said slides 6 are posts, as 10, each post being provided with a sleeve 11, which may be movably disposed upon the post and secured in its fixed position thereon by means of a set-screw 12, or other suitably formed fastening means. Connecting the respective sleeves 11 of the oppositely disposed posts 10 may be a tie-rod 13, as shown in Fig. 1 of the drawings.

Other sleeves 14 are also movably disposed

upon said posts 10, said sleeves being adapted to be secured in their adjusted positions upon said posts by means of set-screws 15, or other suitable fastening means. Pivotally connected with said sleeves 14, for any desired angular adjustment, is a suitably formed frame, as 16, in which is suitably mounted and secured a piece of fabric 17, as canvas or the like. In order that the said posts 10 may be rigidly held in their vertically disposed positions, braces or struts, as 18, may be employed, the same being suitably secured to the respective slides 7 by means of screws or pins 20. substantially as illustrated more particularly in Fig. 2 of the drawings.

As shown, the said frame 16 usually comprises a pair of metal end-members 21 and connecting side-members 22, to which the fabric 17 is suitably secured by means of rivets 23. This frame may, however, be otherwise constructed, and if desired, the said side-members 22 may be entirely omitted.

When a foldable frame is desired, as shown in Fig. 3 of the drawings, in lieu of single end-members 21, end-members 24 and 25 which are pivotally connected as at 26, may be employed, whereby the sections of the head-rest thus provided may be folded upon each other, or held in their straightened out relation, substantially as shown and as will be clearly evident from an inspection of said Fig. 3.

As shown in Fig. 1 of the drawings, when the attachment is secured in the position, indicated generally by the character A, then the device is capable for use, either as a rest for the head or shoulder, or as a pillow-sham holder, but when moved into the dotted position, indicated by the character B, and the frame 16 is properly adjusted, then the device can be used as a serving or reading table, or may be used as a work-bench, if desired; and as will be clearly evident.

To use the device or attachment as a draft-preventing means, it is detached from the respective side-rails 3 and 4, and readily secured upon either one of said side-rails, 50 in a position indicated in the dotted outline, at C, the person lying in bed thus being protected from winds or drafts entering an open window or door in close proximity to the bed, as will be readily evident from an inspection of said Fig. 1 of the drawings.

The device or attachment may also be put to other uses in connection with the bed, and by slightly varying the slides and fas-

tening means may be used in connection with the side-rails of a bedstead of a different style and construction from that shown in the accompanying drawings.

I am fully aware that some changes may be made in the general arrangements and combinations of the various devices and parts, as well as the details of the construction of the said parts, without departing from the scope of the present invention as set forth in the foregoing specification, and as defined in the clauses of the claim which are appended thereto. Hence, I do not limit my present invention to the exact arrangements and combinations of the various devices and parts as described in the said specification, nor do I confine myself to the exact details of the construction of the said parts, as illustrated in the accompanying drawings.

I claim:—

1. In a bed-attachment of the character set forth, in combination with the side-rails of a bedstead, slides mounted upon said rails, means for securing said slides in fixed positions to said rails, upright posts extending from said slides, sleeves movably mounted upon said posts, means for securing said sleeves in their adjusted positions upon said posts, a covered frame connected with and pivotally mounted between said sleeves, a second set of slides mounted upon said rails, means for securing said last-mentioned slides to said rails, and stay-rods between said posts and said last-mentioned slides.

2. In a bed-attachment of the character set forth, in combination with the side-rails of a bedstead, slides mounted upon said rails, means for securing said slides in fixed position to said rails, upright posts extending from said slides, sleeves movably mounted upon said posts, means for securing said sleeves in their adjusted positions upon said posts, a covered frame connected with and pivotally mounted between said sleeves, a second set of slides mounted upon said rails, means for securing said last-mentioned slides to said rails, stay-rods between said posts and said last-mentioned slides and a tie-rod connecting said posts.

In testimony, that I claim the invention set forth above I have hereunto set my hand this 5th day of July, 1919.

JOSEPH W. WEISMANTEL.
